UNITED STATES PATENT OFFICE.

GUSTAV A. BADER, OF ROCHESTER, NEW YORK.

EYEGLASS-MOUNTING.

1,174,222.

Specification of Letters Patent.

Patented Mar. 7, 1916.

Application filed March 13, 1913. Serial No. 754,157.

To all whom it may concern:

Be it known that I, GUSTAV A. BADER, a citizen of the United States, and resident of Rochester, in the county of Monroe and 5 State of New York, have invented certain new and useful Improvements in Eyeglass-Mountings, of which the following is a specification.

This invention relates to eye-glass mountings of the type in which nose-engaging members or clamps are carried by arms or levers projecting rearwardly from the plane of the lenses, and the object of the invention is to provide nose-clamp levers of novel 15 and improved form, wherein the sheet-metal of which they are constructed is so shaped, and has its width so disposed, as to provide with greater facility for bending the levers, at various points, to adjust the position of the 20 nose-clamps in accordance with the peculiarities of the person to whom the glasses are to be fitted.

To the foregoing end I employ, in my novel nose-clamp lever, an integral sheet-metal member shaped and bent in such a manner as to provide two substantially U-shaped portions, of which the first, lying adjacent the pivotal support of the lever, has vertical arms in which the width of the 30 sheet-metal lies in parallel planes extending transversely with respect to the eyeglass-mounting as a whole, while the second U-shaped portion springs from one of the vertical edges of the rear arm of the first U-shaped member, and has two arms lying in 35 a substantially horizontal plane, and with the width of the sheet-metal vertical.

In the accompanying drawings: Figure 1 is a plan-view, on a greatly enlarged scale, 40 of one-half of an eyeglass mounting embodying the present invention and; Fig. 2 is a perspective view, on a still larger scale, of the nose-clamp lever shown in Fig. 1.

The invention is illustrated as embodied 45 in an eyeglass mounting having the usual rigid bridge 5, which is connected with each lens 6 by means of the usual lens-clip 7. The end-portion of the bridge is provided with the usual vertical pivot 8, upon which the 50 nose-clamp lever has its bearing.

The nose-clamp lever is formed of sheet-metal, which is cut to a suitable pattern and then bent to shape. It has a flat portion 9 in which the sheet-metal lies horizontally, 55 this portion being perforated to receive the

pivot 8, and being adapted to lie and turn against the upper surface of the bridge. The lever has a forwardly projecting extremity or finger-piece 10, by which it may be operated in the usual manner. The novel 60 form and construction of the lever is embodied in its rearwardly-projecting arm or portion by which the nose-clamp is supported. At a point near to the pivotal part 9 of the lever the metal is bent upwardly and then downwardly, so as to form a vertically disposed U-shaped part having forward and rear arms 11 and 12, respectively, in which the metal lies in planes 65 transverse to the length of the lever. From the rear arm 12 of the U-shaped portion just described the metal then extends directly from one of the vertical edges of the arm, and is bent into the form of a second 70 U-shaped portion disposed horizontally and having arms 14 and 15, in which also the sheet-metal lies in planes transverse to the length of the lever. The rearmost arm 15 serves as a support for the nose-clamp 16. The arm 15 is connected pivotally with the 75 nose-clamp 16 by means of a pivot 29 which passes through the arm and through a lug 17 on the nose-clamp.

The form of the nose-clamp lever above described is such that it lends itself readily 80 to the various adjustments required in devices of the kind in question. The horizontally disposed U-shaped portion is adapted to have its arms bent toward or from each other, so as to adjust the effective length of 85 the lever, while they may also be twisted slightly to change the rearward inclination of the nose-clamps. The height of the nose-clamps may be readily adjusted by bending the lever at the vertically disposed U-shaped portion. The width of the sheet-metal in 90 the various parts of the lever lies in planes which render these adjustments easy and tend to confine the bending to the points where it is most effective.

In addition to the advantages just pointed out, the novel form of the nose-clamp lever has the further advantage that the vertical U-shaped portion provides a pocket or recess 13 adapted to receive the end of the nose-clamp spring. This spring, as illustrated in Fig. 1, is of the usual form, having a coiled portion 20 which surrounds the pivot-stud 8. One end of the spring extends rearwardly 105 from the pivot-stud, and has an extremity 21 110

which is bent so that it may enter the recess 13. In this manner the spring is connected with the lever, and at the same time the extremity 21 is substantially concealed, and is 5 effectually protected against catching in the clothing or person of the wearer.

In addition to the other parts above described the lever is also preferably provided with a downwardly projecting stop-lug 23, 10 which coöperates with the bridge to limit the inward swinging movement of the nose-clamp and the lever.

I claim:

1. In an eyeglass-mounting, the combination, with a bridge, and nose-clamps located in the rear of the bridge, of nose-clamp levers formed integrally of sheet-metal and each comprising a part pivoted to the bridge on a substantially vertical axis, a U-shaped 20 part located close to the rear of the bridge and in front of the corresponding nose-clamp and having substantially vertical arms in which the width of the metal is transverse to the length of the lever so that 25 the arms may be twisted about vertical axes to cause the rear ends of the levers to be swung toward or from each other, and a part extending rearwardly from a vertical edge of the rear arm of the U-shaped part and carrying the nose-clamp at its rear end, the 30 width of the sheet-metal in said part being vertical so that said part may be bent to correct the change in the angular position of

the nose-clamp resulting from the twisting 35 of the U-shaped part.

2. In an eye glass-mounting, the combination, with a bridge and nose-clamps located in the rear of the bridge, of nose-clamp levers formed integrally of sheet-metal and each comprising a part pivoted to 40 the bridge on a substantially vertical axis, a U-shaped part located close to the rear of the bridge and in front of the corresponding nose-clamp and having substantially vertical arms in which the width of the metal is 45 transverse to the length of the lever, so that the arms may be twisted about vertical axes to cause the rear ends of the levers to be swung toward or from each other, and a part extending rearwardly from a vertical 50 edge of the rear arm of the U-shaped part and carrying the nose-clamp at its rear end, the width of the sheet-metal in said part being vertical and said part being curved or bowed, in a horizontal direction, so that 55 said part may be bent to correct the angular position of the nose-clamp, or to vary the distance of the nose-clamp from the bridge without disturbing the adjustment of the 60 distance between the nose-clamps secured by twisting the U-shaped part as aforesaid.

GUSTAV A. BADER.
